UNITED STATES PATENT OFFICE.

EMIL J. BRAUN, OF NEW YORK, N. Y.

HUMIDIFIER.

1,187,570.

Specification of Letters Patent. Patented Apr. 27, 1913.

Application filed December 5, 1894. Serial No. 273,634.

To all whom it may concern:

Be it known that I, EMIL J. BRAUN, a subject of the German Emperor, and a resident of the city of New York, borough of Manhattan, in the county and State of New York, have invented a new and Improved Humidifier, of which the following is a full, clear, and exact description.

The object of the invention is to provide a new and improved humidifier more especially designed for use in rooms and associated with a radiator or other heating medium to supply moisture in an ample quantity to the surrounding atmosphere with a view to properly moisten the same.

In order to accomplish the desired result, use is made of a water receptacle and a moisture distributor extending into the said receptacle, the said distributor being of a permeable material to draw the water by capillary attraction out of the said receptacle and to evaporate the water into the surrounding atmosphere.

A practical embodiment of the invention is represented in the accompanying drawings forming a part of this specification, in which similar characters of reference indicate corresponding parts in all the views.

Figure 1 is a side elevation of the humidifier with parts shown in section; Fig. 2 is an edge view of the same with part of the frame in section on the line 2-2 of Fig. 1; Fig. 3 is a sectional plan view of the same on the line 3-3 of Fig. 1; Fig. 4 is a reduced edge view of the humidifier as applied to the back of a radiator; Fig. 5 is a similar view of the same as applied to the front of a radiator; Fig. 6 is a side elevation of a modified form of the humidifier, parts of the water receptacle and the frame being shown in section; Fig. 7 is an edge view of the same; Fig. 8 is a reduced edge view of the same and shown resting on top of the radiator; Fig. 9 is a side elevation of another modified form of the humidifier; Fig. 10 is a cross section of the same on the line 10-10 of Fig. 9; Fig. 11 is a sectional plan view of the same on the line 11-11 of Fig. 9; and Fig. 12 is a reduced edge view of the

same as applied to a radiator in the usual opening between the columns of the radiator coils.

The humidifier illustrated in Figs. 1, 2, 3, 4 and 5 is mounted on an open frame A, supporting at its lower end a water receptacle B provided at one side with a spout B' projecting beyond the corresponding side of the frame A to permit of conveniently filling the receptacle B with water. Into the water contained in the receptacle B extends a moisture distributor C of a permeable material such as asbestos and the like, and capable of drawing the water out of the receptacle B by capillary attraction and evaporating the water into the surrounding atmosphere.

The moisture distributor C may be of various forms; for instance, as shown in Figs. 1, 2 and 3, it consists of a number of tubes of a permeable material extending through openings in the top of the receptacle B. Each tube of permeable material is surrounded by an open mesh guard D of wire netting or the like, having a bearing in the top of the receptacle B and another one in the top of the frame A, it being understood that each tube and its guard rest on the bottom of the receptacle B, and the upper end of each tube and its guard projects beyond the top of the frame A.

It will be noticed that by the arrangement described the water contained in the receptacle B is readily absorbed by the permeable material of each distributing tube and the water is caused to travel upward in the tube by capillary attraction to be evaporated eventually into the surrounding atmosphere.

In order to aid the evaporation of the water into the surrounding atmosphere, use is made of air supply pipes E extending through the bottom of the receptacle B up into the distributor tubes to a point above the level of the water so that the air can pass through the said air tubes E into the distributor tubes and out of the same at the top thus carrying along the water vapors inside of the distributor tubes.

The humidifier is preferably associated

with a radiator F, either at the back thereof adjacent the wall H, as shown in Fig. 4, or at the front of the radiator, as shown in Fig. 5, or on top of the radiator, as illustrated in Fig. 8, or in the opening between the columns of the radiator coils, as shown in Fig. 10.

For holding the humidifier in position at the back or front of the radiator, as illustrated in Figs. 4 and 5, use is made of hooks G engaging the top of the frame A and hooked onto the connecting rod connecting the radiator coils with each other near the top of the radiator, as will be readily understood by reference to Fig. 5.

In the arrangement shown in Figs. 6, 7 and 8 the water receptacle B² is provided at the top with a filling spout B³ which is inside of the corresponding side of the frame A'. In this case the bottom of the receptacle B² is adapted to be set on top of the radiator F and the moisture distributer C' is preferably formed by two rows of tubes of permeable material each surrounded by a guard D' of wire netting. Air supply tubes E' extend through the bottom of the receptacle B² into the lower ends of the tubes of the moisture distributer C', otherwise the construction is the same as above described in reference to Figs. 1 to 3.

In the modified form shown in Figs. 9, 10, 11 and 12, the water receptacle B⁴ is sufficiently narrow to permit of inserting it into the opening F' between the columns of the coils of the radiator F, and one side of this receptacle B⁴ is provided with a filling spout B⁵ for filling the receptacle B⁴ with water. The frame A² is similar to the one above described in reference to the other frames, and the moisture distributer C² in this case is made in the form of a number of sheets of permeable material set into the receptacle B⁴ from the top and engaged at their upper ends by the top bar of the frame A². Each distributer sheet C² is covered by a guard D² of wire netting. Hooks G are used for suspending the humidifier in the opening F' from the top connecting bar of the radiator F, as shown in Fig. 12.

The operation of the modified forms of the humidifier is the same as above described in reference to the humidifier illustrated in Figs. 1 to 5, so that further description of the same is not deemed necessary.

It will be noticed that by the arrangement described a large evaporating surface is provided to supply moisture in an ample quantity to the surrounding atmosphere. It is understood that as the humidifier is attached directly to the radiator it is evident that the circulating air readily causes a quick evaporation of the water drawn up from the receptacle by the capillary attraction of the permeable material of which the distributers are formed. The water receptacle is replen-

ished with water from time to time as required.

Having thus described my invention, I claim as new and desire to secure by Letters Patent:

1. A humidifier, comprising an open frame, a water receptacle on the lower end of the said frame, a moisture distributer extending with its lower end loosely through the top of the said receptacle into the water contained in the receptacle, the said distributer being of a permeable material, and a perforate guard surrounding the said distributer from the top to the bottom thereof and having a bearing on the top of the said receptacle and on the top of the said frame, the said guard resting at its lower end on the bottom of the receptacle. 70

2. A humidifier, comprising an open frame, a water receptacle at the lower end of said frame, a tubular moisture distributer extending into the water contained in the said receptacle, the said distributer being of a permeable material to draw the water from the said receptacle by capillary attraction and to evaporate the water into the surrounding atmosphere, a perforate tubular guard surrounding the distributer and having a bearing in the top of the receptacle and in the top of the frame, the upper end of the distributer and its guard projecting beyond the top of the frame, and the lower end resting on the bottom of the receptacle and means for conducting air into the lower end of the said distributer. 85

3. A humidifier, comprising an open frame having openings in its top, a water receptacle at the lower end of said frame having its top provided with openings, the said receptacle having an inlet spout at one end projecting beyond the corresponding end of the frame, a plurality of tubular moisture distributers of permeable material, perforated tubular guards surrounding the said distributers from the top to the bottom thereof, the said distributers and their guards extending through the openings in the top of the frame and projecting above the same and also extending through the openings in the top of the water receptacle 105 and resting at their lower ends on the bottom of the receptacle, air supply tubes extending through the bottom of said water receptacle into the tubular distributers and extending at their upper ends above the top 115 of the water receptacle, and suspending means for the humidifier. 120

4. A humidifier, comprising an open frame having top and side bars, a water receptacle held at the lower end of said frame and having an inlet spout at one side projecting beyond the corresponding side of the frame, a moisture distributer of permeable material extending loosely through the top of said water receptacle into the water con- 125 130

tained in the said receptacle, and an open mesh guard covering said moisture distributer from the top to the bottom thereof, the moisture distributer and its guard being held on the top bar of said frame and resting at their lower ends on the bottom of the water receptacle.

In testimony whereof I have signed my name to this specification in the presence of two subscribing witnesses.

EMIL J. BRAUN.
